Primary Examiner — Rob Spear*Assistant Examiner* — Carla Jobe Wright(74) *Attorney, Agent, or Firm* — Banner & Witcoff, Ltd.**(57) CLAIM**

The ornamental design for a handset, as shown and described.

DESCRIPTION

FIG. 1 is a bottom view of a handset showing my new design;
 FIG. 2 is a right side view thereof;
 FIG. 3 is a front view thereof;
 FIG. 4 is a left side view thereof;
 FIG. 5 is a top view thereof;
 FIG. 6 is a rear view thereof; and,
 FIG. 7 is a perspective view thereof.
 In the drawings, the broken lines depict unclaimed environment.
